Primary Examiner — Shannon W Morgan*Assistant Examiner* — Altaira J Swangin(74) *Attorney, Agent, or Firm* — Lawrence G. Fridman, Esq; Feigin & Fridman, LLC(57) **CLAIM**

The ornamental design for a beer barrel holder, as shown and described.

DESCRIPTION

FIG. 1 is a front perspective view of a beer barrel holder showing my new design;

FIG. 2 is a side perspective view thereof;

FIG. 3 is a front elevation view thereof;

FIG. 4 is a rear elevation view thereof;

FIG. 5 is a right side elevational view thereof;

FIG. 6 is a left side elevational view thereof;

FIG. 7 is a top plan view thereof;

FIG. 8 is a bottom plan view thereof;

FIG. 9 is another left side elevation view showing the beer barrel holder of FIGS. 1-8 in an open position thereof; and, FIG. 10 is another left side elevational view showing the beer barrel holder of FIGS. 1-8.

The broken lines in FIGS. 1-3 depict portions of the beer barrel holder that form no part of the claimed design. The broken lines in FIG. 10, showing a barrel, depict environment and form no part of the claimed design.

1 Claim, 9 Drawing Sheets(56)
